(57) **CLAIM**

We claim, the ornamental design for a multifunction printer, as shown and described.

DESCRIPTION

FIG. 1 is a front perspective view of a multifunction printer, showing our new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines illustrating portions of the multifunction printer are for environmental purposes only and form no part of the claimed design.

1 Claim, 6 Drawing Sheets
